United States Patent Office

Des. 182,951
Patented June 3, 1958

182,951

WHATNOT MIRROR OR THE LIKE

Thomas Estella, Long Island City, N. Y.

Application June 19, 1956, Serial No. 41,976

Term of patent 3½ years

(Cl. D33—9)

Fig. 1

Fig. 2

Fig. 1 is a front elevational view of a whatnot mirror or the like embodying my new design; and

Fig. 2 is a section taken on the line 2—2 of Fig. 1.

Fig. 3 is a front perspective view of the mirror.

I claim:

The ornamental design for a whatnot mirror or the like, as shown.
